UNITED STATES PATENT OFFICE

133,496

DESIGN FOR A DISPLAY STAND FOR PENS OR THE LIKE

Paul M. Ressinger, Chicago, Ill.

Application February 21, 1942, Serial No. 105,932

Term of patent 7 years

To all whom it may concern:

Be it known that I, Paul M. Ressinger, a citizen of the United States, residing at Chicago, in the county of Cook and State of Illinois, have invented a new original, and ornamental Design for a Display Stand for Pens or the like, of which the following is a specification, reference being had to the accompanying drawing, forming part thereof.

Fig. 1 is a perspective view of a display stand for pens or the like, showing my design; and

Fig. 2 is a vertical mid-sectional view thereof.

I claim:

The ornamental design for a display stand for pens or the like, as shown.

PAUL M. RESSINGER.
